APPARATUS FOR TREATMENT OF THE FEET

De Forest B. Catlin, Wareham, Mass.

Application June 6, 1942, Serial No. 446,008.

5 Claims. (Cl. 272—57)

This invention relates to improvements in apparatus for treatment of the feet and more particularly to apparatus through use of which the bones of the feet will be restored to their proper positions and the muscles of the feet will be exercised, the apparatus while in use being fully under the control of the patient and not requiring an operator other than the patient.

The wearing of improperly fitting shoes, lack of exercise or improper walking may lead to various pathological conditions of the feet. Treatment of such conditions has been by foot exercises performed by the patient or manual therapy applied by the hands of a podiatrist.

The object and purpose of the improved apparatus herein disclosed is to enable a patient by the use of the apparatus to attain the corrective results which would be accomplished by a trained and expert manual therapist while at the same time the foot muscles are exercised to retain the corrections and adjustments.

It is particularly an object of my invention to provide apparatus which may be used in the home by the patient to simultaneously exercise both feet while at the same time corrective pressure is applied to produce flexing of the bones of the foot and return of the arches of the foot to their normal positions.

It is a further object of my invention to provide apparatus which may be used for the treatment of the feet in a variety of positions with the patient either sitting or standing, the variably applied weight of the body being used to produce the corrective pressure.

Another object of my invention is the provision of apparatus consisting of a base and a pair of pivoted pedals adapted to be engaged by the plantar surfaces of the pair of feet, the pedals having raised portions thereon to engage the longitudinal and metatarsal arches of the feet and being further provided with strap means to produce fixation of the forepart of each foot so that the corrective pressures will be properly applied.

The features of my apparatus which are deemed to be important include the provision of a rigid base or pedal against which the foot is pressed, the base or pedal having arch engaging portions thereon the curvatures of which are emphasized beyond the normal curvatures of the arches, the provision of a pair of pedals adapted to be simultaneously engaged by both feet enabling the apparatus to be held in place by one foot while tension is being applied by the other foot, and the provision of means comprising straps for pro-

ducing fixation of the foreparts of the feet to produce twisting and flexing of the bones of the feet as pressure is applied to the arches.

Further objects and advantages of my improvements will be more readily apparent from the following description of a preferred embodiment thereof as illustrated in the attached drawings, in which:

Fig. 1 is a perspective view showing my improved device for treatment of the feet;

Fig. 2 is an end elevation of the device;

Fig. 3 is a vertical section taken on the plane indicated 3—3 in Fig. 2;

Fig. 4 is a plan view of one of the pedals, the strap member being broken away for clarity;

Fig. 5 is a transverse vertical section of the pedal, showing a modified adjustment of the strap;

Figs. 6, 7 and 8 are perspective views showing a pair of feet associated with the device in three different positions of use.

The device for the treatment of the feet as disclosed includes a rigid base comprising the platform 10, the forward bottom edge 12 of which rests upon the floor while the rear or heel end is held in a raised position from the floor by the rest member or foot 14. The device is intended to be freely movable about on the floor but when lateral pressure is applied by the feet the device is prevented from sliding as the forward edge 12 makes a sharp contact with the floor.

A pair of pedals 16 and 18 are pivotally mounted on the platform 10. Spring hinge members 20 are used to connect each pedal to the base.

The lower hinge part 22 is fastened to the base in any suitable manner such as by the screw bolts 24 secured in position by the nuts 26, while the upper hinge part 28 is fixed to the pedal by the screws 30. The pair of hinge parts 22 and 28 are connected by the pivot pin 32 and the hinge parts are normally held in the position shown in Fig. 3 through the provision of the coil spring 34 whereby the pedal is in raised position.

In Fig. 3 the heel end of the pedal is in contact with the platform 10, a suitable cushion or bumper 36 being used if desired so as to soften the contact. Similarly, cushion stops 38 may be applied to the forward end of the pedal to cushion the contact of the forward end of the pedal with the platform 10 when the pedal is pushed down by the foot. Each pedal is made long enough and wide enough to accommodate large feet as well as small feet.

Each pedal is shaped or specially constructed to provide a pressure member for the longitudinal

arches of the foot comprising the inner longitudinal arch and the outer longitudinal arch or the weight bearing portion of the outer side of the foot. The top surface of the pressure member for the longitudinal arches of the feet is preferably formed substantially cone-shaped as shown. The members 40 may be separately shaped and attached to each pedal by the screws 30. These conical pressure members are arranged transversely with respect to the foot pedals with the large ends of the cones adjacent the inner edges of the pedals. It will be understood that the members 40 may be formed as complementary parts of a single cone which is turned to the desired curvature and then split longitudinally to provide the parts 40 which are attached as described. It should be further noted that the outer end of each of the conical members 40 is preferably formed with a raised arcuate portion 42 which serves as a stop or abutment by engaging the outer longitudinal arch of each foot. The curvature of the pressure members 40 is designed to exaggerate the curve of a normal arch so that when the foot is applied to the pedal and pressure applied thereto a more pronounced curvature will be imparted to the longitudinal arch of the foot.

In addition to the provision of the conical members 40, I provide on each pedal a cylindrical-shaped member 44 which extends forwardly from the mid portion of the conical member 40. Each member 44 is smoothly rounded at its forward end. The members 44 form the pressure members which engage the metatarsal arch of each foot. Each of the members 44 is secured to the associated pedal by the provision of a screw 46. It should be particularly noted that each member 44 is made long enough to accommodate feet of varying sizes and it is not necessary to provide any adjustment as the metatarsal arch will always come in contact with the member 44 at some portion of its length.

In order that the device may be effectively used, some means must be employed to hold the forepart of the foot in position and I provide for this purpose the strap members 48. The ends of each strap are turned and stitched together to provide the looped portions 50 which engage the rods 52. A pair of the rods 52 extend along the sides of each pedal and the rods 52 are fixed at their forward ends by the screws 54. The rear ends of the rods 52 engage the stop members 56, the outer ends of which are downwardly turned as shown in Fig. 5. The rods 52 may be pushed downward in order to permit removal of the strap 48 from the rods.

The straps 48 may also be adjusted as illustrated in Fig. 5. In this figure one of the looped ends 50 of the strap has been removed from one of the rods 52 and the strap passed between the rod and the side wall of the pedal. In this position the strap is shortened which may be desirable for small feet. It will be understood that the stop members 56 serve to hold the rods against upward movement when tension is applied to the straps. The straps may be readily adjusted longitudinally of the pedals to fit feet of varying sizes and to vary the strap tension by which the feet are held in position.

Treatment of the feet by manual therapy is well known in which the hands are used to apply corrective pressure to the foot. Manual therapy on the foot is performed with the foot relaxed and without any cooperation being required from the patient. After correction by manual therapy, the

foot must be strapped or taped in order to prevent immediate return of the bones of the foot to the position before treatment.

It is also well known that there are certain exercises which can be performed to improve the condition of the feet, but in such foot exercises the foot is not held in position by pressure so that a stretch may be applied between the point of pressure and a fulcrum as is the case in manual therapy.

The device which I have disclosed provides means by which the advantages of manual therapy are combined with the advantages of foot exercises. With my device both feet are placed in position on the pedals as shown, for example, in Fig. 6. The transverse conical members tend to raise the longitudinal arch of the foot. The metatarsal portion of the foot is applied against the cylindrical-shaped surface of the member 44 against which it is held by the strap 48. The device may be used with the patient in a seated position in which position the individual feet may be alternately pressed forward and retracted by movement of the pedals up and down. In Fig. 8, for example, the left foot has pressed the pedal down and serves to hold the base of the device in position while the right foot and the associated pedal is raised. The patient or user may apply just the desired amount of pressure. Initially the feet may be tender and too much pressure may cause pain and discomfort. Therefore, only a small amount of pressure may be first applied but the pressure may be increased as the foot condition improves. With the patient in a seated position, spreading the knees apart tends to apply more pressure to the outer longitudinal arches of the feet. Furthermore, the user may slide the device on the floor forward or to the side to increase the strain. Thus in Fig. 7 the legs are at a sharp angle with respect to the base of the device and a twisting pressure is applied to the feet.

In order to obtain more effective pressure than can be applied with the user of the device in a sitting position, the user may be standing up as is the case in Fig. 6. In this position the entire weight of the body is transmitted to the plantar surfaces of the feet which are resting upon the arch supporting projections on the pedals. In the standing position the feet may be alternately moved up and down as in walking and the muscles of the legs will be exercised as well as the muscles of the feet.

I claim:

1. In a device for the treatment of the feet, a movable pedal adapted to be engaged by the plantar surface of a foot, a member fixed transversely on said pedal having a conical surface adapted to engage the longitudinal arch of the foot and a second member extending longitudinally of the pedal forwardly from the first member, said second member having a cylindrical shape adapted to engage the metatarsal arch of the foot and a strap member associated with the pedal adapted to extend over the instep of the foot to hold the forepart of the foot in engagement with the metatarsal arch engaging member.

2. In a device for treatment of the feet, a pivotally mounted pedal adapted to be engaged by the plantar surface of the foot, a transverse member on said pedal having a conical surface adapted to engage the longitudinal arch of the foot, said member having a stop portion to engage the outer side of the foot adjacent the outer longitudinal arch, a second member on said pedal

extending forwardly from the mid point of said first member, said second member being cylindrically curved transversely of the pedal and being adapted to engage the metatarsal arch of the foot, said second member having a length sufficient to accommodate feet of varying sizes, a pair of rods fixed to the sides of said pedal and a strap member slidably engaged at its ends by said rods and adapted to extend over the instep of the foot, said strap member being longitudinally adjustable with respect to said rods.

3. In a device for treatment of the feet, a pair of movably mounted foot supports, each of said supports being adapted to be engaged by one of a pair of feet and being movable under pressure applied by the foot, resilient means effective to oppose movement of the foot supports under the action of the foot pressure and arch engaging projections on said foot supports having curvatures effective to spread the bones of the feet which form the arches of the feet, said arch engaging projections comprising a cone-shaped transversely extending projection having an abutment at its small outer end and a longitudinal substantially cylindrical-shaped projection extending forwardly from said cone-shaped projection.

4. In a device for treatment of a foot, a pedal member, means supporting the pedal member for pivotal movement, means on said pedal to engage the longitudinal arches of the foot, means extending forwardly from said first named means to engage the metatarsal arch of the foot, a strap

member adapted to extend over the forepart of the foot, a pair of rods fixed to and extending along the sides of said pedal the forward ends of said rods being pivoted to said pedal, stop members on said pedal adapted to be engaged by the rear ends of said rods, said strap member having loops at its ends slidably engaged by said rods to permit adjustment of the position of said strap member with respect to said pedal.

5. In a device for the treatment of the feet, a base adapted to rest on a supporting surface comprising a platform, a support fixed to the rear end of the platform at an angle thereto whereby the base is supported at the forward end by the platform and at the rear end by the support, said platform being normally forwardly and downwardly inclined with respect to the supporting surface, a pair of foot pedals pivotally mounted between the ends thereof on said platform, resilient means effective to rock the pedals to bring the rear ends thereof into stopped position against the raised rear end of the base with the pedals forwardly and upwardly inclined with respect to the supporting surface, conical arch supporting projections on the pedals near the rear or heel ends thereof, the large ends of the conical projections being disposed toward the inner sides of the pedals, cylindrical metatarsal arch supporting projections forwardly extending from the conical projections on each pedal, and strap means for holding the feet on the pedals.

DE FOREST B. CATLIN.
